ELECTRIC SIGNAL SYSTEM

Filed Oct. 11, 1927

INVENTOR
THOMAS H. THOMAS
BY *John M. Brady*
ATTORNEY

UNITED STATES PATENT OFFICE

THOMAS H. THOMAS, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA

ELECTRIC SIGNAL SYSTEM

Application filed October 11, 1927. Serial No. 225,478.

This invention relates to signal systems, and more particularly to an electric signal system adapted for use on railway trains.

An object of my invention is to provide a train signal system by the use of which a trainman may signal the engineman from any car of a train and by which the engineman may cause his reply signal to be transmitted to the car station from which the trainman's signal originated, and further by which the engineman may, under certain conditions, signal any number of car stations at which the trainman may desire to receive the engineman's signal.

Another object of my invention is to provide an electric signal system for railway trains, in which, there is a source of direct current and a signal indicating device on each vehicle of the train, each device being adapted, at one time, to transform the direct current from said source, to alternating current to operate at least one other device, and at another time, being operative by alternating current supplied from one of the other of the devices.

These and other objects will appear from the following more detailed description of the invention.

In the accompanying drawing, the single figure is a diagrammatic view of a train signal system embodying my invention.

According to my invention, the locomotive or controller car of a train may be provided with an engineman's switch device 1, a source of direct current such as the generator 2 and a signal indicating device 3.

The switch device 1 may comprise a casing having a contact member 4 slidably mounted therein, which is adapted to be moved in one direction manually, and in the opposite direction by a spring 5 which is interposed between the member and a plug 6 having screw-threaded engagement with the casing, which plug has a stop 7 adapted to limit the movement of the contact member in one direction. In order to prevent rotative movement of the contact member, a bushing having screw-threaded engagement with the casing, is provided with a pin 8 which engages the contact member within a slot 9. The

contact member is provided with a contact 10 which extends through the member and projects slightly beyond the sides thereof. The projecting ends of this contact are adapted to be moved into contact with contact terminals 11 and 12, the terminal 11 being connected with the generator 2 and the terminal 12 being connected with one end of a primary winding or coil 13 of the signal indicating device 3, the other end of the coil 13 being connected to an interrupter 14 of the device which is normally held in contact with a contact 15 by a spring 15^a, which contact 15 is connected with the generator 2. This signal device besides comprising a coil 13 and an interrupter 14, also comprises a core or armature 16 and a secondary winding or coil 17, one end of such coil being connected to ground at 18 and the other end being connected to a train wire 19.

Each car of the train may be provided with a trainman's switch device 20, a source of electric current such as the battery 21, a signaling indicating device 22 and a jack switch 23.

The trainman's switch device 20 may comprise a casing containing a sliding contact member 24 having an operating stem 25 adapted to be operated by a lever 26 having operating arms 27 and 28, each having an operating cord 29 connected therewith. Mounted on the casing, there are fulcrum pins 30 and 31 which are so disposed that when the arm 27 is operated the lever 26 turns about the fulcrum pin 30 and when the arm 28 is operated, the lever 26 turns about the fulcrum pin 31 and in either case the stem 25 is operated. The contact member 24, when moved a predetermined distance, engages a yielding stop member 51 which is subject to the pressure of a spring 52 mounted in the casing. The contact member is yieldably maintained in its normal position as shown in the drawing by a spring 53. To prevent rotative movement of the contact member 24, a bushing having screw-threaded engagement with the casing, is provided with a pin 32 which is adapted to engage the member within a slot 33. This contact member 24 is provided

with contacts 34 and 35 which are insulated from each other and which extend through and project outside of the member. The contact 34, in the second position of the contact member 24, is adapted to control the circuit wires connected to contact terminals 36 and 37, and the contact 35 is adapted to control the circuit wires connected to contact terminals 38 and 39. The terminal 36 is connected to the positive terminal of the battery 21 and the terminal 37 is connected to one end of the primary winding or coil 40 of the signal device 22, the other end of the coil being connected to the interrupter 41 which is normally held in contact with a contact 42 by a spring 43, which contact 42 is connected to the negative terminal of the battery 21. The contact terminal 38 is connected to ground at 44 and the terminal 39 is connected to one end of the secondary winding or coil 45 and to a tine 46 of the jack switch 23, which switch also has a tine 47 spaced from the tine 46 and is connected to ground at 48. A plug 49 is adapted to be inserted between these tines to connect them. The coils 40 and 45 are wound upon a core or armature 50. In the third or lowermost position of the contact member 24, the contact 35 connects the contact terminals 38 and 39 and the contact 34 will be below and out of contact with the contact terminals 36 and 37. Assuming the several parts of the system to be in their normal positions, as shown in the drawing, and the trainman desires to signal the engineman, the trainman pulls the cord 29 until the contact member 24 comes to rest against the yielding stop member 51, at which time the contact 34 will connect the contact terminals 36 and 37, and the contact 35 will connect the terminals 38 and 39. The connecting of the terminals 36 and 37 permits current to flow from the battery through the coil 40, interrupter 41 and contact 42 of the signal device 22 and from thence back again to the battery. Current flowing through the coil 40 causes the core 50 to be magnetized so that it draws the interrupter to it and out of engagement with the contact 42, thus opening the circuit and demagnetizing the core 50 and permitting the spring 43 to move the interrupter 41 again into contact with the contact 42 to close the circuit, and these operations continue so long as the contact member 24 is maintained depressed to its second position. Current flowing through the coil 40 induces an alternating current in the coil 45, train wire 19, coil 17 of the signal device 3 to ground 18, which causes the interrupter 14 to operate to sound a signal to the engineman. If the trainman desires to receive a reply to the signal initiated by him or a signal initiated by the engineman, he inserts the plug 49 between the tines 46 and 47 of the jack switch at each of the car stations where it is desired to receive the engineman's sig-

nal, thus connecting one end of the coil 45 of the signal device 22 to ground 48, or if he desires he may depress the contact member 24 to its third position in which the contact 35 will connect the contact terminals 38 and 39 thus connecting one end of the coil 45 of the signal device 22 to ground 44. Now if the engineman desires to signal the trainman, he depresses the contact member 4, of the switch device 1, until it comes to rest against the stop 7, at which time, the contact 10 connects the contact terminals 11 and 12, thus closing the circuit from the generator 2, through contact 15, interrupter 14 and coil 13 of the signal device 3, to the generator, and current flowing through the coil 13, will induce an alternating current in the coil 17, through train wire 19 and coil 45 of the signal device 22 and jack switch 23, to ground 48, or through the trainman's switch to ground 44, in the event of the contact member 24 being in its third position, which causes the signal device 22 to operate to sound a signal to the trainman. In the present embodiment of the invention the signal indicating devices 3 and 22 are identical in construction and the secondary coils thereof are connected in series so that when one of these coils supplies alternating current to the other, the core of the signal device being supplied with alternating current, will be magnetized and will draw the interrupter out of engagement with the adjacent interrupter contact. When the interrupter of the signal device supplying the alternating current is in its circuit opening position there is a pause in the alternating current which causes the core of the signal device being supplied with alternating current to be demagnetized, so that the interrupter spring thereof will return the interrupter to its normal position, and these operations will continue so long as the circuit is closed, to sound a signal.

The cores 16 and 50 of the signal devices 3 and 22, respectively, have each been shown of inverted U shape with the primary winding on one leg and the secondary winding on the other leg, but this has been done for the purpose of more clearly illustrating the invention. In practice, each of these signal devices may have a single core upon which the primary and secondary coils may be wound.

While one illustrative embodiment of the invention has been described in detail, it is not my intention to limit its scope to that embodiment or otherwise than by the terms of the appended claims.

Having now described my invention, what I claim as new and desire to secure by Letters Patent, is:—

1. In an electric train signal system, the combination with a train wire, of a signal indicating device on each vehicle of a train connected to said train wire and to ground

and operable by alternating current, a source of direct current, and means included in each signal device for transforming current from said source to alternating current and for supplying said alternating current over said train wire to at least one of the other of said devices.

2. In a train signal system, the combination with an electrically controlled signal indicating device on one vehicle of a train and connected to ground, of an electrically controlled signal indicating device on each of the other vehicles of the train and each connected to ground, a source of direct current on each vehicle, an electric circuit on each vehicle for supplying direct current to the local signal device, and a train wire connecting said devices, any one of said signal devices when supplied with direct current being operative to transform said direct current to alternating current and to supply said alternating current to at least one other signal device over said train wire to operate said other device to effect a signal.

3. In a train signal system, the combination with a train wire connected to ground, of an electrically controlled signal indicating device on each vehicle of the train and connected to said train wire, of a source of direct current on each vehicle, means on each vehicle operative to supply current from one of the sources of direct current to one of the signal devices, and induction means embodied in each signal device adapted when supplied with direct current to supply alternating current over said train wire to operate at least one of the other of said devices to effect a signal.

4. In a train signal system, the combination with a train wire connected to ground, of a signal indicating device on one vehicle of a train and operable by alternating current flowing through said train wire, a signal indicating device on each of the other vehicles of the train operable by alternating current flowing through said train wire, means located at one station on each of said other vehicles of the train under the control of an operator for supplying alternating current to said train wire for energizing the first mentioned signal device, said means including at least one of the second mentioned signal devices, and means located at the station on the first mentioned vehicle and under the control of an operator for supplying alternating current to said train wire for energizing at least one of the second mentioned signal devices, the last mentioned means including the first mentioned signal device.

5. In a train signal system, the combination with a signal indicating device on one vehicle of a train, a source of electric current on said vehicle adapted to supply direct current to said device, a train wire connected to said device and to ground through said

device, means whereby direct current supplied to said device will be transformed into alternating current and supplied to said train wire, a signal indicating device on each of the other vehicles of the train connected to said train wire adapted to be operated by the alternating current flowing through said train wire, and means whereby direct current supplied to at least one of the second mentioned signal indicating devices is adapted to be transformed into alternating current and supplied to said train wire to operate the first mentioned signal indicating device.

6. In a train signal system, the combination with a signal indicating device on one vehicle of a train operable by alternating current and a signal indicating device on each of the other vehicles of the train operable by alternating current, each of said devices being connected to ground, of a source of direct current on each vehicle, manually controlled means for connecting one of the sources of current with at least one of said signal devices, and means included in each signal device for transforming the direct current supplied thereto into alternating current, and a train wire for conducting said alternating current to at least one of the other of said devices to operate it.

In testimony whereof I have hereunto set my hand.

THOMAS H. THOMAS.
